FISHHOOK SHARPENER

William J. Marks, Des Moines, Iowa

Application August 10, 1953, Serial No. 373,311

5 Claims. (Cl. 76—88)

This invention relates to a tool for sharpening a point end of a fishing hook or like and is an improvement on my co-pending application on a sharpening tool, Serial Number 326,386, filed December 17, 1952.

The present and universal method of sharpening the points of fishhooks is to whet and hone the same with a small abrasive stone. Obviously, this is a slow and tedious task due to the curvature and shank of the hook being adjacent and in the way of the sharpening action. In the case of multiple hooks, such as found on fishing plugs, the sharpening operation is almost impossible and often results in injury to the one sharpening the hooks. However, the hooks on such baits are particularly subjected to point damage and this is especially so when the plug is being cast in water having boulders and rocks.

Therefore, the principal object of my invention is to provide a fishhook sharpening tool that is as easy to operate as that of sharpening a pencil or winding a watch.

A further object of this invention is to provide a fishhook sharpener that once in operational contact with the fishhook, requires little skill or further attention from the user except the mere manual rotation of the same.

A still further object of my invention is to provide a fishhook sharpening tool that evenly grinds the point of the fishhook into sharpened condition without lateral swinging moments during the rotation of the tool.

A still further object of my invention is to provide a fishhook sharpener that is self-cleaning.

Still further objects of my invention are to provide a sharpening tool of the class described that is economical in manufacture, durable in use, and refined in appearance.

These and other objects will be apparent to those skilled in the art.

My invention consists in the construction, arrangement, and combination of the various parts of the device, whereby the objects contemplated are attained as herein-after more fully set forth, specifically pointed out in my claims, and illustrated in the accompanying drawings, in which:

Fig. 1 is a perspective view of my tool ready for use in showing a hook in broken lines being sharpened.

Fig. 2 is an enlarged side view of the head portion of the tool with sections cut away to more fully illustrate its construction.

Fig. 3 is a longitudinal sectional view of the device showing its attack of a fishhook point during the sharpening process.

Fig. 4 is an enlarged sectional view of the head portion of the tool with the file unit removed.

Fig. 5 is an enlarged end view of the head of the tool, and

Fig. 6 is an enlarged perspective view of the flat file element.

In these drawings I have used the numeral 10 to designate the body of my sharpener which is in the form of an elongated rod having its upper end 11 knurled to facilitate its manual handling and rotation. The numeral

2

12 designates the other or head end of the tool and in the end of which I have formed a slot opening 13. This slot opening extends inwardly and at an angle to the longitudinal axis of the tool as shown in Fig. 3.

5 In the manufacture of my tool, I drill a transverse hole 14 through the head portion 12, with this hole bisecting the slot 13 as shown in Fig. 4. The numeral 15 designates a small file of rectangular structure inserted into the slot opening 13 as shown in Fig. 2. Inasmuch as the hole 14 passes through and bisects the slot opening 13, the file segment will cross the hole 14 substantially at the center length of the hole 14. The numeral 16 designates a set screw threaded into one end of the hole 14 and engaging the top of the abrasive file element 15 as shown in Fig. 3. By tightening this set screw 16, the file 15 will be rigidly held within the slot 13 as shown in Fig. 1. The other end of the hole 14 will be below the file and will serve as an outlet passageway for filings from the fishhook being sharpened. By this arrangement, my tool will be self-cleaning. Obviously without the hole 14, the file 15 and slot 13 would readily become fouled from the metal removed from the fishhook being sharpened and would necessitate the constant removal of the screw 16 and file 15 for cleaning. However, with my structure, the shavings from the fishhook will readily drop out through the open end of the hole 14.

The numeral 17 designates the hook point passageway in the free end of the head portion 12. This hole 17 is concentric with the tool and extends longitudinally into the tool as shown in Fig. 5. Also it will be noted that the hole 17 and slot 13 are so located that the extreme side of the hole 17 adjacent the slot 13 will be in communication with the same. Due to the angularity of the slot 13, the hole 17 will eventually completely pass into the slot 13 as shown in Fig. 5. As is well known, the barbed end of fishhooks are pointed and to compensate for the increasing diameter of the same from the extreme point end, I have accordingly changed the diameter of the hole 17 as it extends into the tool. By this structure the hole 17 is formed to decrease in diameter as it approaches into the slot 13. In my first experimentations with my sharpeners, I formed this hole 17 of uniform diameter, but found that due to the shape of the barb of the fishhook, two serious objections arose, i. e., the tool would not successfully take different sized hooks, and secondly, the tool objectionably wobbled when rotated. Furthermore, in some cases the point of the hook would not be ground to a thin, sharp taper. However, by the structure 40 of my hole 17, which is in reality, first, a large hole passageway, and then a communicating smaller diameter passageway, I find that many different sizes of hooks may be successfully sharpened to a fine point and furthermore, that the tool will rotate smoothly on its axis without lateral wobbling action. As the side of the hole 17 is in communication with the slot 13, I have beveled the outer edge 18 of the file 15 to aid in guiding the point of the fishhook to be sharpened into the hole 17 and into engagement with the face of the file.

60 In the drawings I have used the numeral 19 to designate an ordinary fishhook.

While I have described my device as particularly adapted for use in the sharpening of fishhooks, it is obvious that the same may be used to sharpen other items such as pins, needles, and like. To sharpen any of these items, it is merely necessary to insert the point of the item to be sharpened into the hole passageway 17 and manually rotate the tool thereon.

70 Some changes may be made in the construction and arrangement of my fishhook sharpener, without departing from the real spirit and purpose of my invention, and it is my intention to cover by my claims, any modified

forms of structure or use of mechanical equivalents which may be reasonably included within their scope.

I claim:

1. In a device of the class described, an elongated body member having a longitudinal hole in one end and a transverse hole extending completely through it, a slot opening in the said end of said body member extending at an angle to the longitudinal axis of said body member, communicating with said longitudinal hole, and bisecting said transverse hole, a flat file member in said slot opening, and a fastening member threaded into one end of said transverse hole and contacting said flat file member.

2. In a device of the class described, an elongated body member having a transverse hole extending completely through it and in its end a longitudinal hole with its entrance bore of greater diameter than the diameter of its innermost bore, a slot opening in the said end of said body member extending at an angle to the longitudinal axis of said body member, communicating with said longitudinal hole and bisecting said transverse hole, a flat file member in said slot opening, and a fastening member threaded into one end of said transverse hole and contacting said flat file member.

3. In a device of the class described, an elongated body member having a longitudinal dead center hole in one end and a transverse hole extending completely through it, a slot opening in the said end of said body member extending at an angle to the longitudinal axis of said body member, communicating with said longitudinal hole and bisecting said transverse hole, a flat file member in said

slot opening, and a fastening member threaded into one end of said transverse hole and contacting said flat file member.

4. In a fishhook sharpener, an elongated body member having in its end and at an angle to the longitudinal axis of said body member a slot opening, a flat file member in said slot, a longitudinal center hole of graduated diameters in the end of said body member, said longitudinal hole communicating with said slot, and means for 10 discharging from said longitudinal opening the filings from a sharpened fishhook.

5. In a fishhook sharpener, an elongated body member having in its end and at an angle to the longitudinal axis of said body member a slot opening, a flat file member in 15 said slot, a longitudinal center hole of graduated diameters in the end of said body members, the most inward of said diameters being smaller than the most outward of said diameters, said longitudinal hole communicating with said slot, and means for discharging from said longitudinal opening the filings from a sharpened fishhook.
